UNITED STATES PATENT OFFICE.

MAX DREXLER, OF MUNICH, GERMANY, ASSIGNOR TO LEONHARD FRIEDRICH BERGDOLT, OF MUNICH, GERMANY.

TOY.

1,043,514.

Specification of Letters Patent.

Patented Nov. 5, 1912.

Application filed August 1, 1911. Serial No. 641,861.

To all whom it may concern:

Be it known that I, MAX DREXLER, a subject of the German Emperor, and residing at Munich, Bavaria, German Empire, have invented certain new and useful Improvements in Toys, of which the following is a specification.

My invention relates to a toy-attachment for suction-pipes, such as mouthpieces for 10 cigars or cigarettes, tobacco-pipes, children's suckers, and the like, which is moved by the sucking action caused when the pipe is in use.

The toy may consist of an articulated doll, 15 puppet, animal, or the like, which is held above or below an opening provided in the suction-pipe and whose movable parts are connected with a sliding-member or piston, in such manner that when the pipe is sucked 20 through by application of the mouth, the piston is drawn inward and causes motion of the parts of the toy with which it is connected.

One embodiment of my invention is illustrated in the accompanying drawing, in which—

Figure 1 is an elevation, and Fig. 2 a sectional fragmental view, while Fig. 3 shows a detail to be hereinafter referred to. 30 The articulated puppet A surmounts a small tube or cylinder c, which accommodates a piston d connected with the limbs e of the puppet by means of members g, which may consist of filaments, strips, or 35 the like. The piston d is normally maintained at the top of the cylinder by means of a compression-spring f. The cylinder c is received by a socket-device b (Fig. 3) having a bent plate or flange a and a strap 40 a¹ or a clip or the like fitting to the suction pipe. The latter is here represented by the cigar-mouthpiece or holder B, and a hole h in the wall of the same constitutes a communication between the interior of the mouthpiece and the inside of the cylinder. The 45 joint between the two parts is tightly closed by the flange a. When the toy is not in use the hole h may be closed in any suitable way.

As already explained, the piston d, under the influence of the helical spring f, is ordinarily held at the top of the cylinder c and the limbs e of the puppet A occupy the positions depicted in Fig. 1. In smoking, however, the suction occurring through the

mouthpiece B draws the piston d inward against the action of the spring f and the limbs e of the figure A are consequently jerked outward. On cessation of the suction, the spring f will return the piston to 60 its initial position and the limbs of the puppet will then be restored to their original positions also. Naturally the spring f can be dispensed with, if the puppet-limbs are of such weight that they drop by gravity into their normal position on the suction ceasing. During smoking the limbs of the toy-figure will thus be kept in a state of motion, that is to say, they will be constantly jerked up and down in a most amusing manner solely owing to the suction resulting from the cigar being smoked. The smoking operation itself is obviously in no wise interfered with.

Having thus described my invention, I 75 declare that what I claim as new and desire to secure by Letters Patent of the United States is—

1. In combination, a suction pipe, an articulated toy having a hollow part communicating with the interior of the pipe, means embracing the latter and connecting it with said hollow part, and a piston located within said hollow part and operatively connected with the movable parts of 85 said toy.

2. In combination, a suction pipe, an articulated toy having a hollow part communicating with the interior of the pipe, means detachably holding the hollow part 90 to said pipe and covering the joint between the two, and a piston located in the hollow part and connected with the movable parts of said toy.

3. In combination, a suction-pipe, an articulated toy, a tubular member communicating with the interior of the pipe and having a flanged attachment which fits over the latter and tightly closes the joint between tubular member and pipe, and a piston 95 located in the tubular member and connected with the movable parts of the toy.

4. A toy-attachment for suction pipes, comprising an articulated toy having a hollow part with openings at the ends, a piston operating within said hollow part and operatively connected with the movable parts of the toy, and detachable flanged fastening means adapted to hold the attachment to a 105 suction pipe.

5. A toy-attachment for suction pipes, comprising an articulated toy presenting a hollow, open-ended part and having a bent terminal flange adapted to embrace a suction pipe, and a piston located within said hollow part and connected with the movable parts of the toy.

6. A toy-attachment for suction pipes, comprising an articulated toy presenting a hollow part, an annular extension thereon adapted to embrace a suction pipe, and a piston operating within said hollow part and connected with the movable parts of the toy.

7. A toy-attachment for suction pipes, 15 comprising an articulated toy having a hollow part, a spring actuated piston located within said hollow part and connected with the movable parts of the toy, and detachable flanged fastening means adapted to hold the attachment to, and in communication with, a suction pipe.

In testimony whereof I affix my signature in presence of two witnesses.

MAX DREXLER.
